(57) **CLAIM**

The ornamental design for an apparatus for gas distribution, as shown and described.

DESCRIPTION

The patent or application file contains at least one drawing executed in color. Copies of this patent or patent application

publication with color drawing(s) will be provided by the Office upon request and payment of the necessary fee.

FIG. 1 is a first side view of an apparatus for gas distribution;

FIG. 2 is a second side view thereof;

FIG. 3 is a third side view thereof;

FIG. 4 is a fourth side view thereof;

FIG. 5 is a top side view thereof;

FIG. 6 is a bottom side view thereof;

FIG. 7 is a first isometric view thereof;

FIG. 8 is a second isometric view thereof;

FIG. 9 is a third isometric view thereof;

FIG. 10 is a fourth isometric view thereof;

FIG. 11 is a fifth isometric view thereof;

FIG. 12 is a second bottom side view thereof;

FIG. 13 is a sixth isometric view thereof;

FIG. 14 is a second top side view thereof;

FIG. 15 is a fifth side view thereof;

FIG. 16 is a sixth side view thereof;

FIG. 17 is a seventh side view thereof;

FIG. 18 is an eighth side view thereof;

FIG. 19 is a first side view of an apparatus for gas distribution, showing a second embodiment;

FIG. 20 is a second side view thereof;

FIG. 21 is a third side view thereof;

FIG. 22 is a fourth side view thereof;

FIG. 23 is a top side view thereof;

FIG. 24 is a bottom side view thereof;

FIG. 25 is a first isometric view thereof;

FIG. 26 is a second isometric view thereof;

FIG. 27 is a third isometric view thereof;

FIG. 28 is a fourth isometric view thereof;

FIG. 29 is a fifth isometric view thereof;

FIG. 30 is a second bottom side view thereof;

FIG. 31 is a sixth isometric view thereof;

FIG. 32 is a second top side view thereof;

FIG. 33 is a fifth side view thereof;

FIG. 34 is a sixth side view thereof;

FIG. 35 is a seventh side view thereof;

FIG. 36 is an eighth side view thereof;

FIG. 37 is a first side view of an apparatus for gas distribution, showing a third embodiment;

FIG. 38 is a second side view thereof;

(Continued)

FIG. 40 is a fourth side view thereof;
FIG. 41 is a top side view thereof;
FIG. 42 is a bottom side view thereof;
FIG. 43 is a first isometric view thereof;
FIG. 44 is a second isometric view thereof;
FIG. 45 is a third isometric view thereof;
FIG. 46 is a fourth isometric view thereof;
FIG. 47 is a fifth isometric view thereof;
FIG. 48 is a second bottom side view thereof;
FIG. 49 is a sixth isometric view thereof;
FIG. 50 is a second top side view thereof;
FIG. 51 is a fifth side view thereof;
FIG. 52 is a sixth side view thereof;
FIG. 53 is a seventh side view thereof;
FIG. 54 is an eighth side view thereof;
FIG. 55 is a first side view of an apparatus for gas distribution, showing a fourth embodiment;
FIG. 56 is a second side view thereof;
FIG. 57 is a third side view thereof;
FIG. 58 is a fourth side view thereof;
FIG. 59 is a top side view thereof;
FIG. 60 is a bottom side view thereof;
FIG. 61 is a first isometric view thereof;
FIG. 62 is a second isometric view thereof;
FIG. 63 is a third isometric view thereof;
FIG. 64 is a fourth isometric view thereof;

FIG. 65 is a fifth isometric view thereof;
FIG. 66 is a second bottom side view thereof;
FIG. 67 is a sixth isometric view thereof;
FIG. 68 is a second top side view thereof;
FIG. 69 is a fifth side view thereof;
FIG. 70 is a sixth side view thereof;
FIG. 71 is a seventh side view thereof; and,
FIG. 72 is an eighth side view thereof.
